AUTOMATIC FUEL FEED CONTROL FOR
INTERNAL COMBUSTION ENGINESHerbert C. Edwards, Massillon, Ohio, assignor to
The Timken Roller Bearing Company, Canton,
Ohio, a corporation of Ohio

Application August 14, 1937, Serial No. 159,035

10 Claims. (Cl. 123—140)

This invention relates principally to fuel injection systems for internal combustion engines of the type wherein the fuel is supplied to the engine by a pump operated by and in unison therewith and the quantity of injected fuel is automatically controlled according to the variation of the vacuum in the inlet manifold of the engine at different speeds thereof.

The invention has for its principal objects to provide for adjusting the vacuum for proper idling speed independently of the adjustment obtained by the main throttle valve, to provide for accurately metering small quantities of fuel at idling speed, to obtain a proper initial adjustment of the fuel metering device relative to the governor, to provide an adjustable stop for limiting the maximum feed of the metering device and to provide for simplicity and compactness of construction and economy of design.

In the accompanying drawings, which form part of this specification and wherein like symbols refer to like parts wherever they occur,

Fig. 1 is a side elevational view of a Diesel engine air inlet manifold and fuel pump provided with an automatic fuel feed control embodying my invention.

Fig. 2 is a view looking at the governor end of the fuel pump.

Fig. 3 is a vertical central longitudinal section through the governor on the line 3—3 in Fig. 2.

Fig. 4 is a horizontal central longitudinal section on the line 4—4 in Fig. 3.

Fig. 5 is a perspective view of the divided or forked arm for manually shutting off the fuel supply and for cooperating with the adjustable stop which limits the maximum quantity of injected fuel.

Fig. 6 is a transverse section through the air inlet conduit or manifold at the butterfly valve and valved by-pass.

Fig. 7 is a vertical section through the by-pass on the line 7—7 in Fig. 6.

Fig. 8 is a central longitudinal section through said manifold on the line 8—8 in Fig. 6.

Fig. 9 is a side elevation of the inlet end portion of the manifold, showing the adjustable stops for positioning the butterfly valve in its full throttle and idle throttle positions; and

Fig. 10 is a diagram illustrating in inches of mercury the manifold vacuum between full load and no load, and the speed of the engine in revolutions per minute at idling and full throttle positions of the butterfly valve of the intake manifold.

Fig. 1 of the accompanying drawings illus-

trates in side elevation an air inlet passageway or manifold A of a multi-cylinder internal combustion engine of the Diesel type and a multi-cylinder fuel feeding device or pump B for supplying accurately measured charges or liquid fuel to the respective cylinders of said engine. As shown in Fig. 1, said pump comprises a housing 1 containing a shaft 2 that is operated by and in unison with the engine and has a separate tappet or cam 3 thereon for actuating the pump unit for each working cylinder of the engine. As shown in Fig. 1, said cam actuates a tappet cup 4 that is reciprocable in the pump housing 1 and, in turn, actuates a spring retracted plunger or piston 5 that reciprocates in a cylinder 6 provided therefor in said housing.

The cylinder 6 is provided with two ports, an inlet port 7 and an overflow port (not shown); and a valved discharge passageway 9 leads from the compression chamber 10 of said cylinder to the engine cylinder supplied thereby. The pump plunger or piston 5 has an annular groove 11 therein that communicates with the compression chamber 10 of the cylinder 6 through a longitudinal groove 12, whereby delivery of the fuel begins as soon as the plunger covers the ports 7 and 8 and ends when the annular groove 11 of the plunger is placed in communication with the overflow or bypass port 8. The groove 11 is provided with a helical upper edge 13, whereby the effective feed stroke of the plunger may be regulated by turning said plunger in its cylinder. The plunger turning mechanism comprises a rack 14 that is reciprocable in a horizontal bore provided therefor in the pump housing 1 and cooperates with the teeth of a sleeve 15 that has an axial slideable but nonrotary connection with said plunger. This type of fuel injection pump is well known and it is considered unnecessary to illustrate it in detail.

The quantity of fuel delivered by the pump B is automatically controlled by a governor C that is operated by the vacuum in the engine inlet manifold A. Said governor comprises a housing 16 that is mounted on one end of the pump housing 1 and is provided with an expanding and contracting chamber 17, the inner end wall of which is formed by a piston or diaphragm comprising a metal disk 18 that is connected at its peripheral edge to the wall of said governor housing by means of a fluid tight accordion or bellows-like member 18a of rubber or other flexible material that permits movement of said disk endwise of said housing and thus increases or decreases the volumetric content of said chamber.

The effective area of the diaphragm is equal to the area of the mean circle between the outside diameter of the bellows neck and the inside diameter of the governor housing, whereby a maximum area and travel of the diaphragm may be obtained with a governor housing of minimum dimensions.

A relatively light compression coil spring 19 is interposed between the disk or piston 18 and the outer end of said housing and tends to force said disk toward the inner end of said pump housing and thus increase the volume of the governor chamber 17. A relatively heavy spring 20 is mounted in a sleeve 21 that is threaded through the outer end of the governor housing in axial alignment but normally out of contact with the axially movable piston or disk 18. The sleeve 21 is provided with a nut 22 for locking it in the desired position of its axial adjustment.

As shown in Fig. 4, the control or rack rod 14 of the pump extends through an opening provided therefor in the inner end wall of the governor housing 16 and is connected by means of a cap screw 23 to a bracket member 24, which has a stud 25 that extends through a central circular opening in the disk 18 into the vacuum or pulsation chamber 17 where it is threaded to receive a nut 26 for clamping said bracket to said disk.

Journalized in the governor housing 16 between the inner end wall thereof and the disk 18 is a horizontal rock shaft 27, one end of which extends outside of said housing and is provided with a rock arm 28 adapted to be movably operated by a suitable pull rod 29. Fixed to the rock shaft 27 within the governor housing 16 is a divided lever 30 having two upwardly extending arms 31 and 32, respectively. The arm 31 is adapted to bear against the rear end of the bracket 24 that connects the axial movable disk or end wall 18 of the expansible chamber 17 with the rack rod 14 of the pump. The other arm 32 of said lever is adapted to bear against an adjustable stop member in the form of a screw 33 that is threaded through the inner end wall of the governor housing 16 in abutting relation to said last mentioned other arm. The space in the governor housing between the inner end wall thereof and the vacuum chamber 17 is open to the atmosphere through an opening 34 in the bottom of said housing; and said chamber communicates with the inlet manifold A through a pipe or other suitable conduit 35.

Threaded on the inlet end of the engine manifold A is an elbow or angle fitting 36 that is provided with a suitable air inlet valve 37. The suction pipe 35 leading from the engine manifold A to the vacuum chamber 17 of the governor is connected by a nut 38 with the outer end of a nipple 39 which is threaded into a radial bore provided therefor in an outstanding flange 40 formed on the inlet end of the angle inlet fitting. A venturi 41 is mounted in the inlet end of the angle inlet fitting 36 and the nipple 39 extends through said venturi and opens into the bore thereof.

Located in the venturi 41 is a butterfly or throttle valve comprising a disk 42 mounted on a horizontal shaft 43 that extends through a diametral bore provided therefor in the flange 40 of the inlet fitting 36 at right angles to the nipple 39 and substantially in the horizontal plane thereof. The shaft throttle valve 43 is journaled in bearings or bushings 44, 44a provided therefor in the inlet fitting 36 and extends exteriorly

thereof where it is provided at one end with an arm 45 having a push-and-pull connection 46 with a suitable accelerator pedal or other actuating device (not shown). Said end of said butterfly valve shaft 43 is also provided with an arm 47 adapted to cooperate with a pair of adjustable stops in the form of screws 48 that are disposed one on each side of said shaft and are threaded through outstanding lugs 49 provided therefor on the inlet fitting 36 and are provided with lock nuts 50. When the arm 47 on the butterfly valve shaft 43 is in contact with one of the stop screws 48, the butterfly valve 42 is in fully opened position; and when said arm is in engagement with the other stop screw, said valve is in a nearly closed position with the nipple opposing side thereof disposed between the inner end of the nipple 39 and the inlet end of the angle fitting 36.

The nipple 39 is provided intermediate between the ends thereof with one or more radial ports 51 that open into an annular chamber 52 that surrounds said nipple and communicates with the inner end of a by-pass passageway or bore 53 that extends through the flange 40 of said inlet fitting parallel to and substantially in the horizontal plane of the butterfly valve shaft 43. The outer end of the bore 53 is closed by means of a suitable plug 54; and a second bore or by-pass passageway 53a leads inwardly from the outer face of the angle fitting flange 40, intersects the bore 53 and opens into a radial port 55 of the butterfly valve shaft supporting bushing or bearing 44a. The portion of the valve shaft 43 journaled in this bushing is provided with a longitudinal groove 56 adapted, in the throttling position only of the butterfly valve 42 to communicate at one end with the radial port 55 of said bushing. The other end of the longitudinal groove 56 opens into an annular space 57 provided therefor at the inner end of the bushing 44a; and said annular space opens into a vertical passageway 58 provided between the bore of the angle fitting and venturi. As shown in Fig. 8, the upper end of the vertical passageway 58 opens into the interior of the inlet fitting 36 between the inlet end thereof and the butterfly valve 42. The outer end of the bore or passageway 53a is closed by means of a threaded member 59 that terminates at its inner end in a needle valve portion 59a adapted to regulate the flow of air from the inlet side of the butterfly valve 42 to the suction passageway, pipe or conduit 35 leading to the vacuum chamber governor.

The fully opened or full throttle position of the butterfly valve 42 provides an unrestricted inlet of air with the result that the vacuum in the engine manifold A is a minimum and rises very gradually when the speed of the engine is increased. In this full throttle position of the throttle valve 42, the vacuum in the engine manifold is insufficient to move the disk 18 against the pressure of the spring 19 with the result that the fuel control rack rod 14 of the pump is not actuated but remains in a position that will cause a maximum quantity of fuel to be delivered by the pump. As shown by the full throttle curve 60 on the diagram of Fig. 10, the vacuum rises very gradually with speed. In this diagram, the light horizontal lines indicate the manifold vacuum in inches of mercury; and two heavy horizontal lines marked 61 and 62 indicate the range in manifold depression in changing from no load to full load; and the numbers at the base of said diagram indicate in hundreds the revolutions per minute of the engine shaft. The intersection of the curved 75

line 60 with the horizontal full load line 62 indicates the maximum R. P. M. where the manifold vacuum allows full throttle operation, i. e. 2560 R. P. M. As the engine speed increases from this point to the point where the curve 60 intersects the horizontal no load line 61, the manifold vacuum increases slightly and no load is reached at 2820 R. P. M. The vertical distance between the horizontal full load lines 62 and no load line 61 in the diagram indicates the range of manifold vacuum in inches of mercury between full throttle position and no load position of the throttle valve. The main governor spring 19 is of such strength that it is fully extended at the point of intersection of the curve 60 with the full load line 62 so as to hold the control rod 14 in maximum fuel delivery position, and is fully compressed at the point of intersection of said curve with the no load line 61 so as to hold said control rod in minimum fuel delivery position. A different position of the throttle valve brings about a different range of speeds. For example, at $\frac{2}{3}$ throttle position as shown on the diagram by the curve 63, the speed range is from 1400 R. P. M. to 1750 R. P. M.

Also it is desirable, to vary the load on the main spring 19 to correctly position the control rod 14 of the pump which is attached to the diaphragm disk 18 to suit the maximum speed. This adjustment of the spring 19 is obtained by the use of shims 19a of varying thickness between the outer end of said spring and the outer end wall of the governor housing 16. By this arrangement, any degree of high speed vacuum can be accommodated to a particular desired maximum engine speed.

The idling vacuum produced when the throttle valve is in idle throttle position is approximately from $\frac{3}{4}$ to one inch mercury for satisfactory idling. Accordingly, it is desirable to put a certain amount of load on the engine when idling, in order to create stable idling conditions. Also, different makes of engines require different quantities of fuel to run idle at high and low speeds. Some engines may require more fuel at high speed than at low speed and others more fuel at low speed than at high speed. Accordingly, if more fuel is required at high speed, the vacuum at such speed must be less in proportion than the quantity of fuel required at low speed.

The idling condition is indicated on the diagram by the curve 64. As indicated by this curve, full load speed is reached at the point where said curve intersects the horizontal full load line 62 and is approximately 390 R. P. M.; and no load speed is indicated at the point where said curve intersects the horizontal no load line 61 and is approximately 425 R. P. M. When the engine has a sufficient amount of manifold vacuum to produce stable running, this small variation in speed is difficult to control with the main spring 19. Accordingly, the heavier spring 20, which more nearly follows the slope of the vacuum curve 64, is brought into operation during the idling speeds. The heavier spring 20 acts as a bumper and surge spring and properly locates the diaphragm disk 18 to accurately meter the small quantities of fuel required during idling. As shown on the diagram, the low speed idling vacuum is exactly the same as the high speed idling vacuum, which means that the spring 20 is also effective during high speed no load conditions and in effect increases the vertical distance between the curves 61 and 62. As the high speed range between full load and no load conditions should be

kept as small as possible, the spring 20 should also be kept as weak as possible and still remain effective to stabilize low speed idling. In view of this condition, the throttle valve 42 is accurately set for idling position by means of one of the stops 48 to obtain the proper low speed idling vacuum. In order to adjust the vacuum to obtain the proper suction in the governor chamber 17 for idling speed, the valve controlled by-pass 53, 53a, is brought into operation whenever the throttle valve 42 is moved into idling speed position. In this position of the throttle valve, the longitudinal groove 56 in the valve shaft 43 is placed in communication with the by-pass 53, 53a, thereby establishing communication between the governor chamber 17 and the portion of the intake manifold located between the inlet end thereof and said valve, so that the full vacuum brought about by the restriction of the manifold passageway by the valve is not fully effective at said governor chamber due to the additional amount of air supplied by said by-pass to the passageway leading to said chamber. By adjusting the needle valve 59 in the by-pass or auxiliary air supply passageway 53, 53a, the idling vacuum in the governor chamber 17 can be varied and adjusted to the spring 20, thereby making it possible to keep the governor adjustments at high speed separate from the governor adjustments at low speeds, by keeping the vacuum at each of these speeds adjusted to produce the position of the control rod 14 required for pumping the proper quantity of fuel whether the idling quantity be greater or less than the high speed quantity.

The bracket 24, which connects the diaphragm disk 18 with the control rod 14 of the pump bears against the free end of the arm 31 of the forked lever 30, and said arm may be actuated by the control rod 29 so as to shift the diaphragm disk 18 outwardly against the pressure of the spring 20 and thus operate the control rod 14 of the pump to shut off the supply of fuel. The other arm 32 of said lever bears against the stop screw 33, which can be adjusted to limit the opening movement of the control rod 14 and thus fix the maximum quantity of fuel which can be pumped.

What I claim is:

1. In an automatic fuel feed control for an internal combustion engine, an air inlet manifold, a throttle valve in said manifold, a fuel feeding device including a control member for regulating the quantity of fuel supplied by said device, a governor having a chamber which communicates with said manifold between said valve and said engine and has a movable wall operatively connected to said control member to reciprocate the same, a spring interposed between said movable wall of said chamber and the opposite wall thereof for urging said control member to maximum fuel delivery position, means for adjusting the maximum fuel delivery position of said control member, and means in addition to said adjusting means for adjusting the tension of said spring. 50

2. In an automatic fuel feed control for an internal combustion engine, an air inlet manifold, a throttle valve in said manifold, a fuel feeding device including a control member for regulating the quantity of fuel supplied by said device, a governor having a chamber which communicates with said manifold between said valve and said engine and has a movable wall operatively connected to said control member to reciprocate the same, a spring interposed between said movable wall of said chamber and the opposite wall thereof, a pivoted, manually operable arm cooperating 65 70

with said movable wall for moving the latter against the pressure of said spring, an adjustable stop cooperating with said movable wall for varying the maximum fuel delivery position of the control member operated thereby, and means for adjusting the tension of said spring.

3. In an automatic fuel feed control for an internal combustion engine, an air inlet manifold, a throttle valve in said manifold, a pump for supplying fuel to said engine, a reciprocable rod associated with said pump for controlling the quantity of fuel supplied thereby, a governor having a chamber which communicates with said manifold between said valve and said engine and has a movable wall operatively connected to said rod to reciprocate the same, a spring interposed between said movable wall of said chamber and the opposite wall thereof, a pivoted, manually operable arm cooperating with said movable wall for moving the latter against the pressure of said spring, a second arm movable with said first mentioned arm, an adjustable stop cooperating with said second arm for varying the maximum fuel delivery position of said rod, and means for adjusting the tension of said spring.

4. In an automatic fuel feed control for an internal combustion engine, an air inlet manifold, a throttle valve in said manifold, a pump for supplying fuel to said engine, a reciprocable rod associated with said pump for controlling the quantity of fuel supplied thereby, a governor having a chamber which communicates with said manifold between said valve and said engine and has a movable wall operatively connected to said rod to reciprocate the same, a spring interposed between said movable wall of said chamber and the opposite wall thereof, means for manually moving said movable wall against the pressure of said spring, an adjustable stop for limiting the expansion of said spring, and adjusting shims interposed between one end of said spring and the adjacent end of said chamber for adjusting the tension of said spring to suit the conditions established by the position of the adjustable stop.

5. In an automatic fuel feed control for an internal combustion engine, an air inlet manifold for said engine, a throttle valve in said manifold, a pump for supplying fuel to said engine, a control member associated with said pump for varying the quantity of fuel supplied thereby, a governor having a chamber which communicates with said manifold between said valve and said engine and has a movable wall operatively connected to said control member, a spring mounted in said chamber and bearing against said movable wall and the wall remote therefrom, a stop cooperating with said movable wall for limiting the expansion of said spring, a second spring mounted in said remote wall and adapted to be engaged by said movable wall at a predetermined point of its movement towards said remote wall, means for bodily adjusting said second spring towards and away from said movable wall, said stop being adjustable to vary the maximum fuel delivery position of said control member, and means in addition to said adjustable stop for adjusting the tension of said first mentioned spring.

6. In an automatic fuel feed control for an internal combustion engine, an air inlet manifold for said engine, a throttle valve in said manifold, a pump for supplying fuel to said engine, a control member associated with said pump for varying the quantity of fuel supplied thereby, a governor having a chamber therein which communicates continuously with said manifold between

said valve and said engine and has a movable wall operatively connected to said control member to operate the same, a spring interposed between said movable wall of said chamber and the opposite wall thereof, a second spring mounted in said opposite wall and adapted to be engaged by said movable wall in the throttling position of said throttle valve, and means for establishing communication between said chamber and said manifold between the inlet end thereof and said valve during the throttling position only thereof.

7. In an automatic fuel feed control for an internal combustion engine, an air inlet manifold for said engine, a throttle valve in said manifold, a fuel pump for said engine, a control member associated with said pump for varying the quantity of fuel supplied thereby, a governor having a chamber that is in continuous communication with said manifold between said valve and said engine and has a movable wall operatively connected to said control member, and means operable only in the throttling position of said throttle valve for establishing communication between said chamber and said inlet manifold between the inlet end thereof and said throttle valve.

8. In an automatic fuel feed control for an internal combustion engine, an air inlet manifold for said engine, a throttle valve in said manifold, a fuel pump for said engine, a control member associated with said pump for varying the quantity of fuel supplied thereby, a governor having a chamber with a movable wall operatively connected to said control member, a conduit communicating at one end with said chamber and at the other end with said manifold between said throttle valve and said engine, a passageway communicating at one end with said conduit and at the other with said manifold between the inlet end thereof and said throttle valve, and means operable by said throttle valve for cutting off flow through said passageway except in the throttling position only of said throttle valve.

9. In an automatic fuel feed control for an internal combustion engine, an air inlet manifold for said engine, a throttle valve in said manifold, a fuel pump for said engine, a control member associated with said pump for varying the quantity of fuel supplied thereby, a governor having a chamber with a movable wall operatively connected to said control member, a conduit communicating at one end with said chamber and at the other end with said manifold between said throttle valve and said engine, a passageway communicating at one end with said conduit and at the other end with manifold between the inlet end thereof and said throttle valve, a valve in said passageway for regulating the flow therethrough, and valve means operable with said throttle valve for cutting off flow through said passageway except in the throttling position only of said throttle valve.

10. In an automatic fuel feed control for an internal combustion engine, an air inlet manifold for said engine, a throttle valve in said manifold, a fuel pump for said engine, a control member associated with said pump for varying the quantity of fuel supplied thereby, a governor having a chamber with a movable wall operatively connected to said control member, a conduit communicating at one end with said chamber and at the other end with said manifold between said throttle valve and the said engine, a shaft journaled in said manifold for operating said throttle valve, said shaft having a longitudinal groove therein in continuous communication at one end

5 with said manifold between the inlet end thereof and the throttle valve therein, and a passageway communicating at one end with said conduit, the other end of said groove being adapted to communicate with the other end of said passageway in the throttling position only of said throttle to

thereby establish communication between said conduit and said manifold between the inlet end thereof and said throttle valve only in said throttling position of said throttle valve.

5 HERBERT C. EDWARDS.
